UNITED STATES PATENT OFFICE.

WILLIAM H. GARLAND, OF KANSAS CITY, MISSOURI, ASSIGNOR OF ONE-HALF TO RAYMOND M. HAVENS, OF KANSAS CITY, MISSOURI.

LOOSE-LEAF BOOK DEVICE.

No. 877,187.

Specification of Letters Patent.

Patented Jan. 21, 1908.

Application filed August 19, 1907. Serial No. 389,322.

To all whom it may concern:

Be it known that I, WILLIAM H. GARLAND, citizen of the United States, residing at Kansas City, in the county of Jackson and 5 State of Missouri, have invented certain new and useful Improvements in Loose - Leaf Book Devices, of which the following is a specification.

My invention relates to loose leaf book devices and more especially to that class comprising a casing, a pair of bars within and 10 rockingly mounted at their outer edges on the casing and slidingly interlocked at their inner edges so that they shall rock in unison, and provided with hooks arranged in sets 15 and adapted when the bars are rocked in one direction to be swung apart and when said bars are rocked in the other direction to come together at their free ends and form rings, and springs interposed between the inner or 20 adjacent edges of the bars and tending to press them apart so as to secure the bars with the hooks in one or the other of the positions referred to, and my object is to produce a 25 device of this character which will operate efficiently and reliably and is of simple, strong, durable and cheap construction.

With this object in view the invention consists in certain novel and peculiar features of 30 construction and organization as hereinafter described and claimed; and in order that it may be fully understood reference is to be had to the accompanying drawing, in which:—

Figure 1, is a top plan view of a loose leaf 35 book device embodying my invention, but with the top plate of the casing omitted. Fig. 2, is a central vertical section taken on the line II—II of Fig. 1, with the top plate of the casing in place. Fig. 3, is a vertical trans- 40 verse section taken on the line III—III of Fig. 2. Fig. 4, is a detail perspective view of a part of one of the hook-carrying bars.

In the said drawing, 1 indicates a channelled bottom-plate of inverted-arch form in 45 cross section.

2 indicates a channelled top-plate of arch form in cross-section and adapted to be snapped onto plate 1 and to form in conjunction therewith the casing of the device, 50 the top plate being provided at suitable points with openings 3.

4 indicates a pair of parallel bars having 55 their outer edges rockingly mounted in the channels of the bottom-plate and equipped in any suitable manner with oppositely

bowed hooks 5 extending up through the slots 3 and provided with serrated free ends 6, the serrated ends of each set of hooks being adapted to interlock together as shown in Figs. 1 and 3 or to be spaced apart as 60 shown by dotted lines, Fig. 3. The inner edges of the bars are adapted to be formed with projecting tongues 7 of substantially right-angle form in cross-section, the tongues 7 of each bar being spaced apart a distance 65 slightly exceeding the width of a tongue. The bars are of identical construction but are reversed with respect to each other so that one tongue of each bar shall fit snugly in the space between the tongues of the other bar, 70 with the tongues of each bar underlying the inner edge of the other bar. By this arrangement the upward movement of the inner edges of the bars is limited by the impingement of the tongues of each bar against 75 the lower side of the companion bar and independent longitudinal movement of the bars is prevented by the disposition of one of the tongues of one bar between those of the other bar, it being understood of course in this 80 connection, that the same effect can be accomplished by providing one of the bars with a pair of tongues and the other with a single tongue between said pair of tongues. This construction however would necessitate the 85 employment of separate dies whereas by providing each bar with a pair of tongues a single die can be employed to produce both bars.

At opposite sides of the tongues 7 each bar 90 is provided with one or more sets of substantially right-angle shaped tongues 8 and 9; the former depending and the latter projecting upwardly from the bars, with the tongues of one of the bars disposed at one 95 side of the tongues of the other. By this arrangement the tongues 8 and 9 of the two bars conjointly form a longitudinal passage and fitting in said passage is a pair of piano-wire or equivalent spring rods 10, the parts 100 being so proportioned that the springs are under slight tension when the hook-carrying bars are depressed or elevated below or above the plane of their pivotal action, the tension on the springs increasing as the bars 105 approach such plane. By this arrangement it is obvious that the springs by outward pressure against the inner edges of the bars or rather against the tongues 8 and 9 on the inner edges of the bars, will tend to hold the 110

bars yieldingly depressed or elevated at such edges and hence will hold the serrated edges of the hooks together or apart as indicated in Fig. 3 by full and dotted lines respectively.

- 5 To open the rings, the hooks are grasped above the top plate and pulled apart, this action overcoming the resistance of the springs and causing the bars to rock upward to the position shown by dotted lines, Fig. 3.
- 10 While the rings are open the perforated loose leaves, not shown, are slipped upon the hooks. The hooks are then pressed toward each other so as to again overcome the resistance of springs 10 and cause the bars to 15 swing downward to the position shown in full lines, Fig. 3, it being noted that the serrated edges of the hooks interlock to complete the rings so as to insure their proper connection and utilize the strength of the springs in 20 holding them closed, it being further noticed that by the provision of the opposite downwardly and upwardly projecting tongues 8 and 9 for the reception of the springs, the hooks are compelled to move in unison with 25 out regard to whether equal power is applied on both sets of hooks in opening or closing the rings. In fact the entire power may be applied on the ring of one bar and yet both bars will operate in unison.
- 30 From the above description it will be apparent that I have produced a loose leaf book device embodying the features of advantage enumerated as desirable, and I wish it to be understood that I reserve the right to make 35 such changes as properly fall within the spirit and scope of the appended claims.
- Having thus described the invention what I claim as new and desire to secure by Letters Patent, is:—
- 40 1. A loose leaf book device, comprising a channel plate, bars rockingly mounted at their outer edges on the channel plate and provided with oppositely-disposed upwardly-projecting hooks having their free edges 45 adapted to interlock or to be spaced apart, tongues projecting downwardly and upwardly from the inner edges of the bars and conjointly forming a longitudinal passage between them, and a spring fitting in said 50 passage and pressing outward against said bars.
2. A loose leaf book device, comprising a channel plate, bars rockingly mounted at their outer edges on the channel plate and 55 provided with oppositely-disposed upwardly

projecting hooks having their free edges adapted to interlock or to be spaced apart, tongues projecting downwardly and upwardly from the inner edges of the bars and conjointly forming a longitudinal passage 60 between them, a spring fitting in said passage and pressing outward against said bars, and a top plate secured to and bridging the channel plate and provided with openings through which said hooks extend.

3. A loose leaf book device, comprising a channel plate, bars rockingly mounted at their outer edges on the channel plate and provided with oppositely-disposed upwardly-projecting hooks having their free edges adapted to interlock or to be spaced apart, tongues projecting downwardly and upwardly from the inner edges of the bars and conjointly forming a longitudinal passage 65 between them, a pair of tongues projecting from the inner edge of one of the bars, a tongue projecting from the inner edge of the other bar and fitting snugly between the pair of tongues, and longitudinally alined springs fitting in the passage formed by and between the said upwardly and downwardly projecting tongues and exerting an outward pressure on the hook-carrying bars.

4. A loose leaf book device, comprising a channel plate, bars rockingly mounted at 70 their outer edges on the channel plate and provided with oppositely-disposed upwardly-projecting hooks having their free edges adapted to interlock or to be spaced apart, tongues projecting downwardly and upwardly from the inner edges of the bars and conjointly forming a longitudinal passage 75 between them, a pair of tongues projecting from the inner edge of one of the bars, a tongue projecting from the inner edge of the other bar and fitting snugly between the pair of tongues, longitudinally alined springs fitting in the passage formed by and between the said upwardly and downwardly projecting tongues and exerting an outward pressure on the hook-carrying bars, and a top plate secured to and bridging the said channel plate and provided with openings through 80 which said hooks project.

In testimony whereof I affix my signature, in the presence of two witnesses.

WILLIAM H. GARLAND.
